Primary Examiner—Freda S. Nunn*Assistant Examiner*—Kevin K. Rudzinski(74) *Attorney, Agent, or Firm*—Harness, Dickey & Pierce, P.L.C.(57) **CLAIM**

The ornamental design for the electric light, as shown and described.

DESCRIPTION

FIG. 1 is an upper perspective view of the electric light, showing my new design;

FIG. 2 is a lower perspective view of the electric light shown in FIG. 1;

FIG. 3 is a front elevation view of the electric light shown in FIG. 1;

FIG. 4 is a back elevation view of the electric light shown in FIG. 1;

FIG. 5 is a left side elevation view of the electric light shown in FIG. 1;

FIG. 6 is a right side elevation view of the electric light shown in FIG. 1;

FIG. 7 is a top plan view of the electric light shown in FIG. 1; and,

FIG. 8 is a bottom plan view of the electric light shown in FIG. 1.
